US0D1063901S

(12) **United States Design Patent** (10) **Patent No.:** **US D1,063,901 S**
(45) **Date of Patent:** **** Feb. 25, 2025**

(54) **ANTENNA**

(71) Applicant: **Lanto Electronic Limited**, Kunshan (CN)

(72) Inventors: **Bo Sun**, Kunshan (CN); **Rong Fu**, Kunshan (CN); **Xiange Yang**, Kunshan (CN); **Tonghui Xiao**, Kunshan (CN)

(73) Assignee: **LANTO ELECTRONIC LIMITED**, Kunshan (CN)

(**) Term: **15 Years**

(21) Appl. No.: **29/881,147**

(22) Filed: **Dec. 28, 2022**

(30) **Foreign Application Priority Data**

Oct. 26, 2022 (CN) 202230710162.X

(51) **LOC (15) Cl.** **14-03**

(52) **U.S. Cl.**

USPC **D14/230**

(58) **Field of Classification Search**

(57) **CLAIM**

The ornamental design for an antenna as shown and described.

DESCRIPTION

FIG. 1 is a front perspective view of an antenna showing our new and ornamental design;

FIG. 2 is a rear perspective view thereof;

FIG. 3 is another rear perspective view thereof;

FIG. 4 is a front view thereof;

FIG. 5 is a rear view thereof;

FIG. 6 is a left-side view thereof;

FIG. 7 is a right-side view thereof;

FIG. 8 is a top view thereof; and,

FIG. 9 is a bottom view thereof.

The broken lines in the drawings depict portions of the antenna that form no part of the claimed design.

1 Claim, 9 Drawing Sheets
